LACE WINDER

Eugene L. Tourigny, Leominster, Mass., assignor to United Comb and Novelty Company, Inc., Leominster,
Mass., a corporation of Massachusetts

Application October 27, 1953, Serial No. 27,353

Term of patent 14 years

(Cl. D41—1)

To all whom it may concern:

Be it known that I, Eugene L. Tourigny, a citizen of the United States, residing at Leominster, in the county of Worcester and Commonwealth of Massachusetts, have invented a new, original, and ornamental Design for a Lace Winder, of which the following is a specification, reference being had to the accompanying drawing, forming part thereof, in which:

The figure is a perspective view of a lace winder, showing my new design.

I claim:

The ornamental design for a lace winder, substantially as shown.
